UNITED STATES PATENT OFFICE

2,457,245

TENSION INDICATOR FOR THREADS ON
SEWING MACHINESAlbert H. Larson and Charles W. Fox,
El Dorado, Ark.

Application January 22, 1946, Serial No. 642,760

2 Claims. (Cl. 73—143)

1

This invention relates to a device for indicating the correct tensioning of threads in sewing machines.

It is an object of the invention to provide a device which may be readily secured to threads in sewing machines, and which will indicate whether the tensioning of said threads is too loose, too tight, or correct.

It is a further object of the invention to provide a device of the above character which is simple to operate, rugged and free from maintenance difficulties, which is constructed of relatively few easily fabricated parts, and which is readily assembled and disassembled.

The general objectives to be attained by this invention when used in conjunction with sewing machines are to assure an even tie of the threads, to eliminate loose or loop stitches, wrinkles, drawn or pulled seams and material, breaking of threads, straight thread stitches, ripped out seams and waste of time and material as well as expensive service calls. All the above evils, as well as others, are largely due to improper thread tensions in sewing machines, and the proper and frequent use of this invention will result in proper adjustment of thread tensions, and consequent obviation of the difficulties.

With the above and still further objects, as will hereinafter more fully appear, one embodiment of the invention is described in the following specifications, and illustrated in the accompanying drawings, and the invention is particularly pointed out and defined in the appended claims. Reference is had to the drawings, wherein like numerals of reference apply to the same parts throughout the various figures, and wherein:

Figure 1 is a front elevation of the device;

Figure 2 is a side view, in elevation, of Figure 1;

Figure 3 is a rear elevation of the device;

Figure 4 is a transverse section; taken on a median line of the device;

Figure 5 is a front view of the device with the front cover removed; and

Figure 6 is a view of a detail of the invention.

Referring now to the drawings in detail, it will be observed that the case of the instrument consists of two parts, a front half 1 and a rearward half 2, secured or jointed by means of bolts 3, which extend through holes extending through the rearward half of the case and which engage with threaded holes provided in the front half of the case.

Provided in the rearward face of casing section 1 is a recess 4 which slidably receives a flat control bar 5, provided at one end with a hole 6 having a small V-slot 7 formed in its circumference

of its outer circumference, the bar 5 being provided with a slot 8 and a pin 9 positioned at one side of the slot. The slot 8 fits slidably over the portion of a rotatable shaft 11 within an annular recess 10. The shaft is provided with a diametrical hole 24 at one side of annular recess 10, and a spring 12, having approximately a U-shape, and comprising a bulge 13 in one leg thereof, has its straight leg inserted through hole 24 and its bulged leg embracing the annular enlargement 14 of shaft 11.

At the end opposite to that containing hole 6, the bar 5 is provided with a slot 8 and a pin 9 positioned at one side of the slot. The slot 8 fits slidably over the portion of a rotatable shaft 11 within an annular recess 10. The shaft is provided with a diametrical hole 24 at one side of annular recess 10, and a spring 12, having approximately a U-shape, and comprising a bulge 13 in one leg thereof, has its straight leg inserted through hole 24 and its bulged leg embracing the annular enlargement 14 of shaft 11.

The spring clip projects to one side of the shaft and provides between the portions of the legs adjacent the closed end thereof a guide slot for 20 the pin 9, which extends therebetween.

A second annular shaft enlargement 16 at the opposite side of recess 10 from enlargement 14 is provided with a hole 17, into which is secured one end of a coil spring 18 which surrounds the 25 shoulder 16, the other end of spring 18 being secured to the rearward casing section 2, at 25. This construction serves to provide a force resiliently urging the bar 5 inwardly of the casing.

The shaft 11 is journaled at one end in a bearing 19 located centrally of the front casing section 1, and at its opposite end in a well 20 provided in a boss 21 which is located centrally of the rearward casing section 2, end thrust being taken up by steel ball 26 located in boss 21 between the bottom of well 20 and the corresponding end of shaft 11.

Pressed on an end of shaft 11 which extends slightly beyond the front face 22 of the indicator casing is an indicator pointer 23. An unbreakable crystal 27 is pressed into an annular shoulder in the casing section 1 to cover the pointer 23, as well as the face 22 of the indicator, upon which is provided suitable dial 24.

In assembling the device from its component parts, the recessed portion 10 of shaft 11 is inserted in slot 8 of bar 5 so that pin 9 extends adjacent to hole 24. The straight side of spring clip 12 is inserted in hole 24 with pin 9 between the legs of the spring clip adjacent the closed end thereof. An end of spring 18 is inserted in hole 17 of annular shoulder 16 and the assembly consisting of shaft 11 and bar 5 and its associated springs 12 and 18 applied to casing half 2 slipping the spring 18 over the boss 21 and the shaft end 11 in the well 20, after insertion therein of ball

26. The tail end of spring 18 is now secured to point 25 of the casing section 2, which may involve a small hole in the casing. The front casing section is now applied with bearing 19 over the corresponding end of shaft 11, and bolts 3 are inserted and tightened. Pointer 23 is now pressed on shaft 11 so that it points to the lowest part of scale 24 when bar 5 is at its limiting position within the casing. Crystal 21 is next pressed into the annular seat provided therefor to complete the assembly.

In utilizing the indicator of this device to adjust sewing machines, the sewing machine is threaded and about two inches are sewed. The presser foot of the machine is then raised and the material being sewed is removed. The bobbin thread is attached to the tension indicator and pulled slowly toward the operator. The bobbin tension screw may then be adjusted until the indicator pointer indicates Correct. For adjusting the top thread tension, the presser foot is dropped and the thread removed from the needle and guides up to the thread takeup lever, then the thread is attached to the tension indicator and pulled slowly thereby through the takeup lever. The upper tension regulator may then be adjusted until the indicator pointer reads Correct.

What we claim is:

1. A thread tension indicator comprising a casing having a front section provided with a central opening, and a rear section provided with a marginal recess and a hollow central boss, a shaft journaled at one end in said central opening and at its opposite end in said boss and having an annular recess intermediate the length thereof and transverse holes therethrough, one at each side of said annular recess, a flat control bar slidably received in said marginal recess having in one end an elongated slot receiving the annularly-recessed portion of said shaft and adjacent its opposite end an aperture having a V-shaped extension directed toward the adjacent end of said bar, a pin projecting from said bar adjacent said slot, a U-shaped spring clip having a straight leg inserted through one trans-

verse hole in said shaft and a curved leg embracing said shaft and receiving said pin between the leg portions adjacent the closed end thereof to operatively connect said bar to said shaft, a coil spring having one end received in the other hole in said shaft and its other end secured to said casing, said coil spring surrounding said shaft and said boss and applying a spring force to said shaft urging said bar inwardly of said casing, a dial on the outer face of said casing front section, and a pointer secured on the corresponding end of said shaft overlying said dial.

2. A thread tension indicator comprising a hollow casing having a marginal recess therein, a shaft journaled in said casing, a dial on one outer face of said casing, a pointer secured on said shaft overlying said dial, a control bar extending slidably through said marginal recess, means operatively connecting said control bar to said shaft, and a coil spring connected at one end of said shaft and at its opposite end to said casing and surrounding said shaft to rotate said shaft in a direction to urge said control bar inwardly of said casing, said means operatively connecting said control bar to said shaft comprising a pin on said bar, and a U-shaped spring clip detachably secured to said shaft and receiving said pin between the portions of its legs adjacent the closed end thereof.
